UNITED STATES PATENT OFFICE.

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

Application filed September 19, 1927. Serial No. 220,610.

My invention relates to a slicing machine, and particularly to a slicing machine for slicing meat, which will be light, simple to manufacture and easy to operate. A particular object of my invention is a provision of guard or deflector means for preventing the access of bits of meat, or other materials operated on, from penetrating into the spaces between knife and guard plate, and from 10 penetrating, about the knife, into the knife and knife shaft housing. Other objects will appear from time to time in the course of the specification and claims.

I illustrate my invention more or less diagrammatically in the accompanying drawings, wherein

Figure 1 is a partial rear elevation;

Figure 2 is a section on the line 2—2 of Figure 1;

Figure 3 is a section on the line 3—3 of Figure 1;

Figure 4 is a partial section, similar to Figure 2, showing a variant form of my device; and

Figure 5 is a partial front elevation.

Like parts are indicated by like symbols throughout the specification and drawings.

A generally indicates any suitable base frame or member provided, for example, 30 with the anti-frictional and noise-deadening supports A¹.

Mounted on such base member is any suitable motor means, herein shown as the motor B, from which projects the motor shaft B¹, 35 on which is the driving pulley B² adapted to engage and drive the belt B³, which engages the inclined face channel B⁴ of the pulley B².

C is a knife supporting sleeve mounted upon the base A and including the shield or guard 40 portion C¹. It will be understood that in the form of Figs. 1, 2 and 3 this guard or shield portion is continuous with or extends to the motor housing B and may form part of the generally upwardly projecting housing or frame member C². I do not wish to be limited in my claims to this particular disposition or arrangement, but I find it highly efficient.

Mounted within the sleeve portion C is an 50 inner sleeve D, in which are mounted the ball bearing tracks D¹ to support the balls D² opposed to the inner tracks D³ on the knife shaft D⁴. D⁵ is a channel pulley mounted on the shaft D⁴ and adapted to receive about it the belt B⁸.

E is the knife disk proper, secured to the shaft assembly, for example by a screw E¹, and additionally secured to the pulley D⁵, for example by the screws E². The knife disk is shown as convex, and is peripherally cut away or recessed on its hollow face, as at E⁴, to leave a peripheral portion E⁵ projecting somewhat forwardly from the face of the knife. The periphery of the rear of the knife is rearwardly inclined as at E⁶, terminating in a shoulder E⁷, beyond which the knife is recessed as at E⁸. It will be understood, with reference to Fig. 2, that the inner edge of the shield portion C¹ conforms generally to the recess E⁸, approaching closely thereto and penetrating beneath the edge of the shoulder E⁷.

Referring to Fig. 4, the sleeve C is shown as being provided with an inwardly projecting apron G, about the pulley D⁷. It is further provided with a terminal cylindrical portion G¹, which under some circumstances is preferably reduced, as shown in Fig. 4. Mounted upon such cylindrical portion G¹ is a split ring or other suitable clamping element G², provided with a lock bolt G³ adapted to draw it tightly about the cylindrical portion G¹ to lock it in position thereupon. G⁴ is a shield portion secured to or integral with the split portion G², the inner edge of which closely engages the ledge E⁷ and the recessed portion E⁸ of the knife.

Referring to Figures 1 and 3, H is a scraper blade adapted to approach or to engage the portion E⁶ of the knife. It is provided with a body portion H¹ engaging the face of the apron or shield C¹. In such body portion may be a plurality of adjustment slots H², through which pass the securing and adjusting screws H³. It will be realized that where as the scraper blade H is, in the drawings, shown as applied to the form of Figures 1 and 2, it is also intended to be applied to the form of Figure 4, it being thought that a detailed view to that effect is not necessary for clarity.

J indicates a guard plate secured in any suitable fashion upon the frame of the device, such guard plate lying in the general plane of the knife, or rather in a plane slightly inclined to the plane of the knife, in such fashion that an edge of the guard plate penetrates the recess E⁴ of the knife, as shown in Figure 2.

Referring primarily to Figure 5 the guard plate J may have mounted upon it, for ex-

ample at its lower angular portion J^1 , a scraper J^2 engaging the front face of the knife. Referring to Fig. 2 it will be seen that I employ a gauge plate, generally indicated as K , which lies in a plane generally parallel with the gauge plate J . K' generally indicates a work supporting carriage member and K^2 a guide therefore in the form of a track or rod.

10 It will be realized that whereas I have described and shown a practical and operative device, nevertheless many changes might be made in size, shape, number and disposition of parts without departing from the spirit 15 of my invention. I therefore wish my description and drawings to be taken as in a broad sense illustrative and diagrammatic, rather than as limiting me to the specific showing herein made.

20 The use and operation of my invention are as follows:

It is extremely desirable to prevent the entry of portions of meat or other material into spaces behind the guard plate J or the shield portions C^1 or G^4 . It will be observed that the knife is recessed on both its forward and its rear face, and that the guard plate J penetrates the forward recess and the member C^1 or G^4 the rear recess. It therefore follows that any bits or crumbs of material which pass across the front or rear face of the knife will engage either the guard plate J or the shield C^1 or G^4 , and access to the space behind the guard plate or shield will 35 thereby be prevented.

40 In order to supplement the consequent disposal of such fragments and to clear the edge of the knife itself, I provide the deflector or scraper H , which may closely engage or may positively scrape the inner face E^8 of the periphery of the knife.

I also find it desirable to provide a scraper for the front of the knife and have indicated the scraper member shown in Figure 5, 45 which opposes an inclined blade J^2 to the exposed flat portion of the knife. The guard plate J and gauge plate K lie in parallel planes. The carriage or support K' may be moved along the rod K^2 and past the cutting 50 edge of the knife.

I claim:

55 1. In a slicing machine, a rotary knife and means for rotating it, a guard plate positioned on the forward side of said knife and a guard plate positioned to the rear of said knife, both faces of said knife being recessed to receive the edges of said guard plates adjacent the side of the knife engaging the material being sliced, the recess in the rear face of the 60 knife being concentric with but of lesser radius than the recess in the forward face of the knife.

65 2. In a slicing machine, a supporting structure, a rotary knife mounted in said structure and means for rotating it, guard plates po-

sitioned on the forward and the rear sides of said knife and guard members, both faces of said knife being recessed to receive the edges of said guard members, and scrapers, associated with said guard members, extending outwardly beyond said recesses. 70

3. In a slicing machine, a supporting structure, a rotary knife mounted in said structure and means for rotating it, a guard plate positioned on the forward side of said knife, the knife face being recessed to receive it, and a scraper blade, engaging the face of the knife, associated with said guard. 75

4. In a slicing machine, a supporting and housing structure, a rotary knife mounted on said structure and a knife shaft associated therewith, a bearing member for said knife shaft, a driving connection associated with said knife shaft, a guard member associated with said bearing member surrounding and enclosing said driving connection and extending toward said knife, the rear face of said knife being recessed to receive the edge of said guard member. 80

5. In a slicing machine, a supporting and housing structure, a rotary knife mounted on said structure and a knife shaft associated therewith, a bearing member for said knife shaft, a driving connection associated with said knife shaft, a guard member associated with said bearing member surrounding and enclosing said driving connection and extending toward said knife, the rear face of said knife being recessed to receive the edge of said guard member, and a scraper member, associated with said guard member, adapted to overlie the rear face of said knife beyond the portion enclosed by said guard member. 90

100 6. In a slicing machine, a supporting and housing structure, a rotary knife mounted on said structure and a knife shaft associated therewith, a bearing sleeve for said knife shaft, a driving connection associated with said knife shaft, a guard member surrounding and enclosing said driving connection and extending toward said knife, the rear face of said knife being recessed to receive the edge of said guard member, and a guard plate positioned on the forward face of said knife, the knife being tilted in relation to said guard plate, to bring the cutting arc of the knife forwardly into the plane of said guard plate, the forward face of the knife being recessed to receive an edge of said guard plate. 110

115 7. In a slicing machine, a supporting and housing structure, a rotary knife mounted on said structure and a knife shaft associated therewith, a bearing sleeve for said knife shaft, a driving connection associated with said knife shaft, a guard member surrounding and enclosing said driving connection and extending toward said knife, the rear face of said knife being recessed to receive the edge of said guard member, and a guard 120

125

130

plate positioned on the forward face of said knife, the knife being tilted in relation to said guard plate, to bring the cutting arc of the knife forwardly into the plane of said 5 guard plate, the forward face of the knife being recessed to receive an edge of said guard plate, and a scraper member, associated with said guard plate, adapted to overlie the forward face of said knife beyond the portion 10 covered by said guard plate.

8. In a slicing machine, a supporting structure, a rotary knife mounted on said structure, and means for rotating it, a guard plate positioned forwardly of said knife and a gauge 15 plate, the guard and gauge plates lying in generally parallel planes, the knife being tilted in relation to the guard plate to bring its cutting edge forwardly into the plane thereof, the forward face of the knife being recessed to receive an edge of the guard plate, the guard plate overlying substantially the entire face of the knife, and a scraper member, associated with said guard plate, adapted to overlie the forward face of said knife beyond the portion covered by said guard 20 plate.

9. In a slicing machine, a supporting structure, a rotary knife mounted on said structure, and means for rotating it, a guard plate positioned forwardly of said knife and a gauge 25 plate, the guard and gauge plates lying in generally parallel planes, the knife being tilted in relation to the guard plate to bring

its cutting edge forwardly into the plane thereof, the forward face of the knife being recessed to receive an edge of the guard plate, 35 the guard plate overlying substantially the entire face of the knife, and a scraper member, associated with said guard plate, adapted to overlie the forward face of said knife beyond the portion covered by said guard plate, 40 driving means for said knife, a guard member adapted to surround said driving means, extending toward the rear face of the knife, the rear face of the knife being recessed to receive the edge thereof, and a scraper member, 45 associated with said guard member, adapted to overlie the rear face of said knife beyond the portion enclosed by said guard member.

10. In a slicing machine, a rotary knife and means for rotating it, a guard plate positioned on the forward side of said knife and a guard plate positioned to the rear of said knife, both faces of said knife being recessed to receive the edges of said guard plate adjacent the side of the knife engaging the material being sliced, the recess in the rear face of the knife being concentric with but of different radius than the recess in the forward face of the knife. 50

Signed at Indianapolis county of Marion and State of Indiana, this 26th day of August, 1927.

WILLIAM J. CAMPBELL.
